UNITED STATES PATENT OFFICE.

FREDERICK WEHINGER, OF WATERBURY, CONNECTICUT, ASSIGNOR TO THE WATERBURY CLOCK CO., OF WATERBURY, CONNECTICUT, A CORPORATION.

CLOCK MOVEMENT.

Application filed December 6, 1923. Serial No. 678,837.

To all whom it may concern:

Be it known that I, FREDERICK WEHINGER, a citizen of the United States, residing at Waterbury, in the county of New Haven and State of Connecticut, have invented a new and useful Improvement in Clock Movements; and I do hereby declare the following, when taken in connection with the accompanying drawings and the characters of reference marked thereon, to be a full, clear, and exact description of the same, and which said drawings constitute part of this application, and represent, in—

Fig. 1 a view in front elevation of a clock-movement constructed in accordance with my invention. For clarity of illustration and description, all of the parts are omitted except those with which the invention is directly concerned.

Fig. 2 an underside view thereof.

Fig. 3 a view thereof in vertical, central section on the line 3—3 of Fig. 1.

Fig. 4 a partly disassembled view thereof in side elevation, with the lower portions of the movement-plates in vertical section, showing the bridge and supplementary winding-arbor as removed, and, in broken lines, the main winding-arbor and its gear as drawn forward out of the sleeve-like hub of the turning spring-barrel, which is shown by broken lines as partly removed.

Fig. 5 a detached view in front elevation of the sleeve-like main-spring hub.

Fig. 6 a view thereof in side elevation.

Fig. 7 a detached view in side elevation of the removable main winding-arbor with its driving-gear.

Fig. 8 a detached view in the side elevation of the reducing-gear arbor with its gears.

Fig. 9 a detached view of the main-winding arbor driving-gear, with the D-shaped bearing-shoulder of the arbor in cross-section.

My invention relates to an improvement in that class of clock-movements constructed to permit their main-spring units to be mounted and demounted, without disturbing the other parts of the structure, the object being to produce a simple and convenient clock-movement of this type and also to provide reducing-gears for facilitating the winding of heavy main-springs.

With these ends in view, my invention consists in a clock-movement characterized

by having a running spring-barrel adapted to be mounted and demounted in a plane parallel with the planes of the movement-plates by the removal from it of the main winding-arbor.

My invention further consists in a clock-movement characterized by the employment of a supplementary winding-arbor co-axial with a main winding-arbor passing through a running spring-barrel and removable therefrom for the demounting thereof.

My invention further consists in a clock-movement having certain details of construction and combinations of parts as will be hereinafter described and pointed out in the claims.

In carrying out my invention, as herein shown, I employ a spring-barrel of the type known as a "running barrel" from the fact that it is turned by the spring as the same unwinds and drives the movement. This running-barrel, so-called, comprises a main-wheel 10, a bushing 11 mounted therein, a barrel-casing 12, a barrel-cap 13, and a sleeve-like main-spring hub 14 furnished

with a peripheral hook 15, which is engaged by the inner end of the main-spring 16, the outer end of which is engaged with a hook 17 mounted in the casing 12. At its rear end the hub 14 is formed with a bearing-shoulder 18, which fits into the said bushing 11, and with a squared tenon 19 mounting a ratchet-wheel 20, which has a correspondingly squared opening. A pawl 21, co-acting with the ratchet-wheel, is secured to

the rear movement-plate 22 by means of which the ratchet-wheel is held in place upon the squared tenon of the hub. At its forward end the hub 14 is formed with a bearing-shoulder 23 having bearing in a

bearing-hole 24 in the barrel-cap 13 and projecting slightly forward through the same, so as to bear upon the rear face of the intermediate movement-plate 25.

The said hub 14 mounts a removable main winding-arbor 26, the rear end of which projects through its tenon 19 and turns in a bearing-hole 27 in the rear movement-plate 22. The forward portion of the said arbor is squared as at 28, so as to fit into a squared opening 29 in the forward end of the hub 14, which is thus coupled with the arbor for being turned thereby in winding the spring 16. Toward its forward end the arbor 26 is provided with a bearing-

shoulder 30 having bearing in a bushing 31 mounted in the intermediate movement-plate 25. Forward of the said bearing-shoulder 30, the arbor 26 is formed with a 5 mounting-shoulder 32 slightly smaller in diameter than the shoulder 30 and provided for mounting the main winding-arbor gear 33, which is formed with a D-shaped central-opening 34 fitting over the said shoulder 32, which is correspondingly flattened, as at 35. The main-arbor 26 is extended in front of the D-shaped shoulder 32, to form 10 a stem 36 providing a pivot-bearing for the sleeve 37 of a co-axial, supplementary winding-arbor 38, the said sleeve 37 being formed at its rear end with a socket 39 adapting it to be set over the stem or pivot 36. The supplementary winding-arbor 38 which 15 mounts a winding-gear 40 and which is squared at its projecting forward end, as 20 at 41, for the reception of the usual winding-key, has bearing in a bushing 42 in a bridge 43 removably secured at its ends by screws 44 entering the lower end of the 25 front movement-plate 45 and by screws 46 which pass through the said plate and enter the movement-pillars 47.

The gear 40 aforesaid meshes into a gear 48 located at the forward end of a reducing-gear arbor 49 carrying at its rear end 30 a gear 50 meshing into the gear 33 aforesaid, mounted upon the forward end of the main winding-arbor 26. The reducing-gear arbor 49, which is arranged parallel 35 with the co-axial arbors 26 and 38, is provided at its forward end with a pivot 51 having bearing in a pivot-hole 52 in the bridge 43, and at its rear end with a pivot 53 having bearing in a pivot-hole 54 in the intermediate movement-plate 25, as shown 40 in Fig. 3. By this system of reducing-gears, the power required to wind the heavy main-spring 16 is greatly reduced.

In case it is desired to demount the main-spring-unit for any purpose without disturbing the movement-structure, the bridge 43 is first removed, whereby the supplementary winding-arbor 38 is freed, so that it may be drawn away from the pivot 36 of the main winding-arbor 26 in line therewith, as shown in Fig. 4. It is now possible to draw the main winding-arbor 26 forward, as shown by broken lines in Fig. 4, entirely out of the main-spring hub 14, 55 after which the main-spring barrel may be removed from the movement as a unit in a plane parallel with the plates thereof, as shown by broken lines in Fig. 4. To remount the main spring-barrel, the reverse 60 order of steps is followed.

I claim:

1. In a clock-movement, the combination with movement-plates thereof, of a running main-spring barrel, a sleeve-like hub therefor, a removable main winding-arbor pass-

ing through the said sleeve-like hub and removable therefrom and having bearing in the said plates, and a co-axial, supplementary winding-arbor, one end of which has pivotal bearing upon one end of the said 70 main winding-arbor.

2. In a clock-movement, the combination with movement-plates thereof, of a running spring-barrel, a sleeve-like hub therefor, a removable main winding-arbor passing 75 through the said hub and connected therewith for turning the same for winding the spring, a supplementary winding-arbor co-axial with the said main winding-arbor and pivotally-connected at one end with one 80 end thereof, a reducing-gear arbor arranged parallel with the said supplementary winding-arbor, and reducing-gears connecting the said supplementary arbor, reducing-gear arbor and main winding-arbor. 85

3. In a clock-movement, the combination with movement-plates thereof, of a running spring-barrel, a sleeve-like hub therefor, a main winding-arbor passing through the said hub, removable therefrom and connected therewith for the rotation thereof, a supplementary winding-arbor pivotally connected at one end with one end of the said main winding-arbor, a bridge removably connected with one of the movement-plates 90 and providing a bearing for the said supplementary winding-arbor, and reducing gears connecting the said supplementary and main winding-arbors. 95

4. In a clock-movement, the combination with movement-plates thereof, of a running spring-barrel, a sleeve-like hub therefor, a main winding-arbor passing through the said hub, removable therefrom and connected therewith for the rotation thereof, a supplementary winding-arbor co-axial with the said main winding-arbor and pivotally mounted at one end thereupon, a bridge removably connected with one of the movement-plates and providing a bearing for the supplementary winding-arbor, a reducing-gear arbor having bearing in the said bridge and in one of the said plates, and reducing-gears connecting the supplementary winding-arbor and the said reducing-gear arbor with the main winding-arbor for reducing the power required to wind the spring. 110

5. In a clock-movement, the combination with movement-plates thereof, of a running spring-barrel, a sleeve-like hub therefor projecting at its respective end therefrom, a ratchet-wheel mounted upon one of the projecting ends of the said hub, the other end of which has a squared opening, 115 a removable main winding-arbor passing through the said hub and having a squared portion fitting into the squared opening thereof, whereby the rotation of the arbor rotates the hub, a gear mounted upon the 120 arbor. 125

said arbor adjacent to the squared portion thereof, a co-axial, removable, supplementary winding-arbor pivotally supported at one end upon the said main winding-arbor, 5 and reducing-gears connecting the supplementary winding-arbor with the main winding-arbor.

In testimony whereof, I have signed this specification in the presence of two subscribing witnesses.

FREDERICK WEHINGER.
